UNITED STATES PATENT OFFICE.

HARVEY HADDEN, OF PEEKSKILL, NEW YORK.

CAR-COUPING.

SPECIFICATION forming part of Letters Patent No. 354,636, dated December 21, 1886.

Application filed April 29, 1886. Serial No. 200,515. (No model.)

To all whom it may concern:

Be it known that I, HARVEY HADDEN, a citizen of the United States, residing in the village of Peekskill, in the county of Westchester 5 and State of New York, have invented new and useful Improvements in Car - Couplings, of which the following is a specification.

My invention relates to improvements in car-couplings in which the common form of link is used, and has for its object the lessening of the dangers attending the coupling of cars. This object I attain by the means illustrated in the accompanying drawings, in which similar letters refer to similar parts throughout the several views.

Figure 1 is a longitudinal sectional view of my coupling, showing the position of the parts in readiness for the insertion of the coupling-link. Fig. 2 is a sectional view, showing a 20 coupling with a link and pin in place. Figs. 3 and 4 are views of details to be described.

Referring to the figures, A represents a draw-head constructed in the usual way, except that the openings k are preferably conical-shaped, terminating inwardly in a rectangular chamber, i, of a depth horizontally of the head adapted to receive the several parts. The conical form of the opening k is for the purpose of guiding the coupling-link into the 25 rectangular chamber i. Within the chamber i a block, a, having a slot or opening, j, as shown in Fig. 3, is adapted to move freely. When the block a is in its place, the pin D is inserted in the head, and passes through the 30 opening j in the block, which serves to keep the block in its place.

Between the block a and the bottom of the chamber i the spring E is inserted, as shown in Fig. 2, in which the block is shown partially cut away, revealing the position of the pin D. Fig. 1 shows how the spring acts upon the block, forcing it outward until it is stopped by the pin D.

The head A is provided at c with the usual 45 hole for a coupling-pin. In Fig. 1 is shown how the coupling-pin B, when ready for action, rests on the block a. It is obvious that when a link, as C, is forced against the block a, said block will be pushed back until the pin 50 B will drop within the link C and through

the hole c, as seen in Fig. 2, pin B being partly cut away to show the positions of link and pin.

The spring employed is adapted to the space between the inner end of block a and the bottom of chamber i when the block is in the position shown in Fig. 2. The object of the pin D, which may be permanently inserted, is two-fold: first, to prevent block a being pushed so far in the act of coupling as to damage or possibly crush the spring, and, second, to limit 60 the movement of the block by the spring when pin B is withdrawn.

The rectangular chamber i is so adapted to the form of links most commonly used that when one is in place, as in Fig. 2, the outer 65 free end of the link cannot drop so low as to require the hand to lift it to meet the opposite draw-head.

The line G is supposed to represent the end of a car, on which a shaft, f, is supported in 70 bearings, one of which is represented by g. This shaft may extend the width of a car, and be provided with cranks at the outer ends, as is usual, to enable train-men to handle the coupling-pin without going between the cars.

To the shaft f, just over the draw-head, an arm, F, is attached, and by means of one or more chain-links is connected with the coupling-pin, as shown. Arm F is also connected with a chain, d, which may pass to the top of 80 or within a car, from which points the pin B may be operated. The action will be obvious. Turning the shaft by means of the cranks at either end of the shaft, or pulling on chain d, will cause a lifting of the pin B from its socket, 85 and as link C is withdrawn the block a will move forward under pressure from the spring E, and taking the position shown in Fig. 1, will support the pin B, as shown. A stop, m, may be applied to the shaft f to prevent lifting the pin B farther than necessary.

Fig. 4 is a top view of the draw-head A, the dotted lines indicating the shapes of the openings in the head, the coupling-pin hole c, pin D, and the movable block a.

I do not claim originality in the use of a sliding block to accomplish the purpose herein described, but that my method of adapting it to a draw-head overcomes defects that have been encountered in its employment. Neither 95 100

do I claim originality in the suspension of a coupling-pin from a rock-shaft to be operated from the side of a car, but that the combinations, as claimed, possess new and superior advantages.

Having thus described my invention, what I claim, and desire to secure by Letters Patent, is—

The combination, for the purposes of a safety car-coupling, of the following elements: a draw-head provided with a longitudinal rectangular chamber, *i*, said chamber having a height adapted to support a coupling-link in nearly a horizontal position and a length to receive a sliding block and spring, and terminating at 15 its outer end in a semicircular opening, *k*, a

slotted sliding block, *a*, provided with square ends and a reduced thickness at its central portion, a pin, *D*, to limit the movement of block *a*, and having a strength equal to that 20 of the coupling-pin, a spring, *E*, a shoulderless coupling-pin, *B*, a link, *e*, an arm, *F*, provided with a stop, *m*, a shaft, *f*, a bearing, *g*, secured to the end of a car, and a chain, *d*, all operating together as herein described and 25 set forth.

Signed at Peekskill, in the county of Westchester, State of New York.

HARVEY HADDEN.
